FIG. 1 is a first side, front perspective view of a garment showing our design;

FIG. 2 is a front view thereof;

FIG. 3 is a side view thereof;

FIG. 4 is a second side, front perspective view thereof; and, FIG. 5 is a rear perspective view thereof.

The long-and-short broken lines form an unclaimed boundary around at least a portion of the claimed subject matter, and form no part of the claim. The even-length broken lines, which show the remainder of the article, are directed to environment, represent unclaimed subject matter, and form no part of the claim.

The contrast in shading represents a contrast in appearance only and does not represent any particular color, material, texture or finish.
